E. P. BURNHAM.
AUTOMOBILE RECORD HOLDER.
FILED DEC. 6, 1919.

UNITED STATES PATENT OFFICE.

ELBRIDGE PALMER BURNHAM, OF NEW YORK, N. Y.

AUTOMOBILE RECORD HOLDER.

Application filed December 6, 1919. Serial No. 342,992.

To all whom it may concern:

Be it known that I, ELBRIDGE PALMER BURNHAM, a citizen of the United States, residing at borough of Manhattan, city of New York, in the county of New York and State of New York, have invented certain new and useful Improvements in Automobile Record Holders, of which the following is a specification.

10 It is often desirable for those who own or operate automobiles to keep an account of the cost of the gasoline, oil, tires used and of the repairs and also to know the reading of the speedometer on certain dates to 15 determine the mileage of the car at a certain date. A note book carried in the pocket or in the machine might serve the purpose but it has been my experience that these note books get lost or mislaid at the very time 20 they are needed.

The object of this invention is the provision of an inexpensive, small and compact automobile expense and record holder which is adapted to be attached to the dashboard 25 or windshield in convenient place to have entered thereon the expenses and other data connected with the operation or repair of the automobile.

Other and further objects will be apparent 30 from the following specification.

An embodiment of the invention is illustrated in the accompanying drawings, forming part of this specification, in which,

Figure 1 is a perspective view of the device;

Figure 2 is a vertical cross-section of the device as illustrated in Figure 1;

Figure 3 is a side view of the device as illustrated in Figure 1;

40 Figure 4 is a sectional view taken on the line 4—4 of Figure 3;

Figure 5 is a fragmental view showing the clamp for attaching the record holder to the frame of the windshield.

45 Referring to the drawings, 10 designates the main body of the holder which is of flat tubular shaped construction. This is illustrated in section in Figures 2 and 4. At the top and rear of the main body 10 and integral therewith, is an extension 11, the function of which is to support the main body 10 when the holder is attached to the dashboard by the screws 11^a, and to hold it in position for recording when so attached.

50 12 55 designates holes in the extension 11 for insertion of screws 11^a, when the device is at-

tached to a dashboard. 13 designates a clamp which is used when the device is attached to the windshield frame 14. At the front of the main body portion is a cut-away portion 15 which enables the record of expenses, and other data connected with automobiles, to be placed on the record sheet 16. This record sheet is mounted to run within the tubular body portion 10 from a roll 17 to 60 a roll 18. Ratchets 19 and 20 and pawls 21 and 22 respectively are connected with the rolls 17 and 18 and prevent turning of the rolls in the wrong direction. The springs 23 and 24 hold the pawls 21 and 22, respectively, in contact with the ratchet wheels 19 and 20. Attached to the roll 18 at the end, opposite the ratchet 20, is the knob 25 which is used to wind the sheet from the roll 17 onto the roll 18 and thus expose a 75 fresh portion of the sheet 16 at the cut-away section 15 of the body portion.

At the top of the body portion 10 is a pencil holder 26 within which the pencil is kept in readiness for immediate use.

The manufacture of my preferred embodiment is very simple. The whole device would be stamped out of sheet metal. Then the sides 27 and bottom 28 would be bent in place and the ends joined in any 80 suitable manner as by solder. The lugs 17^a and 17^b would be bent in position to support the roll 17 and in like manner the lugs 18^a and 18^b would be bent to support the roll 18. The thin tubular construction is particularly 85 advantageous in that it provides a structure which is easily made, as above stated, and also is light and provides protection to the paper. This latter feature is essential since in an automobile there is always more or 90 less wind which would render ineffective any device having an unprotected sheet.

When it is desired to make entries on the record sheet, it is only necessary to remove the pencil from the holder 26 and make such 100 entries as desired. When it is desired to remove the used record from the roll 18, it is only necessary to raise the pawl 22, unwind the record from the roll 18 and tear it off on the rear edge 30 of the body portion 10. The paper strip is then attached to the roll 18 by a suitable attaching means and the slack taken up by turning the knob 25.

The use of the clamp 13 is optional. When the record holder is attached to the dashboard, the clamp is first taken off by removal of the screws 31. When attached to

the windshield frame 14, the clamp is used. In this case the extension 11 rests against that part of the frame below the attaching point but no screws 11^a are necessary.

5 It will be seen from the above description that I have provided a device for attachment to an automobile convenient to the operator's seat so that records relating to the expenses or operation of the automobile 10 can be quickly and conveniently made. It is equally clear that with this device the record can be neatly kept and is protected from the wind and is available for reference whenever desired.

15 Having described the invention what is claimed is:—

1. In a record strip holder, a flat tubular body to receive a record strip and having a portion of one face cut away to exhibit a 20 section of the strip, and an extension disposed at an angle to said body for mounting the holder upon a support in an inclined position, the said body and extension being formed from a single piece of sheet material.

2. In a record strip holder, a flat tubular

body adapted to receive a record strip and having a portion of one face cut away to exhibit a section of the strip, lugs attached to said body, an extension disposed at an 30 angle to said body for mounting the holder upon a support in an inclined position, said body, lugs and extension being formed from a single piece of sheet material, a strip holding and moving means mounted in said lugs. 35

3. In a record strip holder, a flat tubular body adapted to receive a record strip and having a portion of one piece cut away to exhibit a section of a strip, lugs attached to said body, an extension disposed at an 40 angle to said body for mounting the holder upon a support in an inclined position, said body, lugs and extension being formed from a single piece of sheet material, the said extension being bent back upon the body to 45 form a pocket, and reels mounted in the lugs and controlling the movement of the record strip through the body, one of said reels being mounted within the pocket formed by the body and extension.

50 In testimony whereof I affix my signature.

ELBRIDGE PALMER BURNHAM.
